United States Patent Office.

JULES DECOUDUN, OF PARIS, FRANCE.

Letters Patent No. 97,614, dated December 7, 1869: patented in France May 16, 1868.

IMPROVED MACHINE FOR IRONING AND STIFFENING LINEN AND OTHER FABRICS.

The Schedule referred to in these Letters Patent and making part of the same.

To all whom it may concern:

Be it known that I, JULES DECOUDUN, of Paris, in the Empire of France, have invented new and useful Improvements in Machinery for Ironing and Stiffening Linen and other Fabrics; and I do hereby declare that the following is a full, clear, and exact description thereof, which will enable others skilled in the art to make and use the same, reference being had to the accompanying drawings, forming part of this specification.

This invention relates to machines for ironing, glossing, and stiffening fabrics, and consists in a machine by which the article is passed between a roll covered with a blanket or equivalent and a concave surface of heated metal.

Figure 1 represents a transverse sectional view of the covered roll and concave bed with the article passing through.

Figure 2 is a vertical transverse section of the whole machine.

D represents a roll, rotated in the direction of the arrow, and covered with a tightly-clasping endless apron, of suitable material. This blanket or apron is marked E.

A is the concave bed, located immediately over the fire, while between them is another chamber, to prevent the too-immediate and intense action of the fire on the bed A.

N M represent a weighted treadle, which is connected with the shaft of the revolving roll or cylinder by means of an ordinary strap.

By means of this treadle, the roll D is elevated, to admit the article to be ironed.

The roll or cylinder may be turned by hand, or driven by any suitable power.

The mode of operation is as follows:

The treadle being pressed, the roll is lifted, and the article inserted. The roll being then let down, and power applied, the friction of the apron or blanket, as it rotates, will slide the article along over the heated bed, and keep it, all the while, under a continuous pressure.

By duplicating the roll and bed, and making a slight modification in the heating-device, an article may be ironed on both sides by the same mode of operation.

Having now described all that is necessary to a clear understanding of my invention,

What I esteem to be of my invention, and desire to protect by Letters Patent, is—

1. The combination of revolving cylinder D, blanket or apron E, and stationary concave heated surface A, constructed and arranged as set forth.

2. The combination of the treadle M, balance-weight N, and connecting-mechanism, with the shaft of the cylinder, to lift said cylinder, in the manner specified.

J. DECOUDUN.
